UNITED STATES PATENT OFFICE.

GERHART GANGELHOFF AND MICHAEL JORDAN, OF MINNEAPOLIS, MINNESOTA.

BED WITH RESILIENT SUPPORT FOR SPRING FRAMES.

Application filed October 10, 1924. Serial No. 742,808.

To all whom it may concern:

Be it known that we, GERHART GANGELHOFF and MICHAEL JORDAN, citizens of the United States, residing at Minneapolis, in the county of Hennepin and State of Minnesota, have invented certain new and useful Improvements in Beds with Resilient Supports for Spring Frames; and we do hereby declare the following to be a full, clear, and exact description of the invention, such as will enable others skilled in the art to which it appertains to make and use the same.

This invention relates to a bed structure and particularly to a means for resiliently supporting the bed spring frame now commonly used in metal and other bed structures. In the structures of the prior art, a rigid bed spring frame has been used which carried the springs supporting the mattress and which frame rested upon the rigid bed frame. It has been found to be very desirable and to afford a much more comfortable bed to have this bed spring frame resiliently supported.

It is an object of this invention, therefore, to provide a bed structure having a resilient supporting means for the bed spring frame.

It is another object of the invention to provide a bed frame of the usual rigid structure having spaced frame members, together with means spanning said members and comprising resilient supports adapted to carry the bed spring frame.

It is a further object of the invention to provide such bed spring frame supporting device which has resilient supports at the sides of the bed, and also has an auxiliary resilient support for the bed spring frame disposed between the said resilient supports.

It is a further object of the invention to provide an article of manufacture adapted to be applied to a bed frame, which article carries spaced means for resiliently supporting a bed spring frame.

These and other objects and advantages of the invention will be fully set forth in the following description made in connection with the accompanying drawings in which like reference characters refer to the same parts throughout the different views and in which,

Fig. 1 is a view in side elevation of a bed embodying the present invention;

Fig. 2 is a vertical section taken on the

line 2—2 of Fig. 1, as indicated by the arrows;

Fig. 3 is a top plan view of one of the bars or units used in the structure;

Fig. 4 is a vertical section taken on the line 4—4 of Fig. 2, as indicated by the arrows;

Fig. 5 is a vertical section taken on the line 5—5 of Fig. 4, as indicated by the arrows; and

Fig. 6 is a view showing a modified form of the invention, Figs. 2 to 6 being shown on an enlarged scale.

Referring to the drawings, in Fig. 1 is shown a bed structure comprising the usual head piece 7 and foot piece 8 between which extend the rigid spaced side members or rails 9 which are secured to the pieces 7 and 8 and preferably detachably secured thereto. A bed spring frame is shown comprising the end members 10 which, in the embodiment of the invention illustrated, are shown as angle bars, between which extend the spring wires 11 secured to the tension springs 12 which are, in turn, secured to the angle members 10. The angle members 10 are secured to and supported by brackets 13 to which reference will later be made. The members 13 are secured to and connected by longitudinally extending members 13^a shown as tubes or pipes extending parallel to the members 9.

A plurality of bars 14 are used which, in the embodiment of the invention illustrated, are two in number, and which extend between and span the space between the side rails 9. While the bars 14 may be of any desired shape, in the embodiment of the invention illustrated, they are shown as of angle shape in cross section and as having arms 14^a at their ends bent substantially at right angles, the outwardly projecting flanges of which conveniently rest on the side rails 9. The vertically extending flanges of said bars are disposed between the side rails 9 and form stops preventing any considerable endwise movement of said bars. Said bars also have rigidly secured thereto arms 14^b spaced a short distance from the arms 14^a so that a pair of spaced arms is provided at each end of said bar. A plurality of coiled tension springs 15 are disposed between and secured at one end to each one of the bars 14^a and 14^b and the other ends of these springs are secured to flanges projecting from each side of the brackets 13

at the bottoms thereof. It will thus be seen that the brackets 13, and hence the bed spring frame members 10 are supported by the springs 15 and thus by the bars 14. In order to steady the bed spring frame and prevent excessive lateral movement thereof, an auxiliary spring support is provided therefor. This auxiliary support comprises a pair of links 16 diverging outwardly and upwardly from the bar 14 and pivoted to the side thereof preferably by a single pivot, said links having rounded upper ends. A tension spring 17 has its ends secured, respectively, to said links above the bar 14 and limits the outward swinging movement thereof. The upper ends of links 16 engage under the horizontal flanges of the angle bars 10 and not only serve to support said bars but also prevent longitudinal movement thereof.

20 The structure described will be preferred when the invention is applied to a new bed. The invention, however, can be applied to beds already in use by simply adding the bars 14 to the bed and allowing the supports of the spring frame to rest thereon. In such a case, the brackets 13 probably would not have the flanges to receive the ends of the springs 15. A plate 18 of rectangular form is then used to which the 25 inner ends of spring 15 are secured, as shown in Fig. 6. The supporting members 19 of spring bed frame are then allowed to rest upon the plates 18. No matter what the shape, therefore, of the bed spring supporting members 19, they may conveniently be received on the plate 18 and will be prevented from any considerable movement thereon, both by the spring 15 and by the links 16.

40 From the above description it is seen that applicant has provided an improved structure of bed and one which will greatly add to the resiliency of the bed and to the comfort thereof. The invention comprises few 45 parts and is easily and quickly installed in either a new bed or a standard bed now in use. The device has been amply demonstrated in actual practice and found to be very successful and efficient.

50 It will, of course, be understood that various changes may be made in the form, details, arrangement and proportions of the parts without departing from the scope of applicant's invention, which, generally stated, consists in a device capable of carrying out the objects above set forth and in the novel parts and combinations of parts shown and described and defined in the appended claims.

60 What is claimed is:

1. The combination with spaced side members of a bed frame and a bed spring frame, of a member extending transversely across said members carrying spaced pairs of coiled springs having their longitudinal

axes extending substantially parallel to said member and resiliently supporting said bed spring frame.

2. The combination with spaced frame members of a bed frame, a bar extending between said members, pairs of springs connected to said bar adjacent each end thereof, the springs of each pair being substantially longitudinally aligned, a member connected to the adjacent ends of each pair of said springs and forming a support for a bed spring frame.

3. The combination with the longitudinally extending spaced frame members of a bed frame, of spaced bars spanning said members, each of said bars having spaced sets of springs thereon, each set comprising opposed substantially horizontal springs, and a member connected to said opposed springs of each set forming the supports for a bed spring frame.

4. The combination with the longitudinally extending spaced frame members of a bed frame, of a bar spanning said members, said bar having spaced rigid substantially parallel portions thereon, a spring secured to each portion, a member between said portions and carried by said springs to form the support for a bed spring frame.

5. The combination with spaced members of a bed frame, of means spanning said members and comprising spaced resilient portions constituting supports for a bed spring frame and also comprising a resilient means intermediate said portions forming an auxiliary support for said bed spring frame, said resilient means being pivoted to the spaced members of the bed frame.

6. The combination with spaced longitudinally extending members of a bed frame, of a bar spanning said members, and having resilient means adjacent each end forming the support for a bed spring frame, and also having resilient means between said first mentioned means adapted to be contacted by and forming a supplemental support for said bed spring frame.

7. The combination with the longitudinally extending spaced members of a bed frame, of a bar spanning said members having a pair of spaced arms at each end, the outer arms of which rest, respectively, upon said members, springs secured at one end to each of said arms and disposed between the same, a member disposed between the arms of each pair and secured at each side to the other ends of said springs, said latter member constituting a support for a bed spring frame.

8. The structure set forth in claim 7, a pair of upwardly diverging links pivoted to said bar, a spring connecting said links above said bar, said links having their upper ends contacted by and supporting said bed spring frame.

9. A supporting unit for a bed spring frame comprising a bar adapted to rest upon and span the spaced members of a bed frame, said bar being of angular shape in cross section and having portions at its ends extending substantially at right angles thereto with their horizontal flanges directed outwardly and adapted to rest on said bed frame members and having their vertical flanges adapted to engage the inner sides of said bed frame members, springs carried adjacent each end of said bar, and a member carried by said springs adapted to form a support for a bed spring frame.
10. A bed spring frame supporting device comprising a member adapted to rest upon the frame members of a bed, and carrying opposed sets of springs extending parallel thereto adjacent its ends a member secured to each of said sets and constituting the supports for a bed spring frame.
11. A bed spring frame supporting device comprising a bar adapted to rest upon the frame members of a bed, and carrying ad-
15. jacent its ends spaced pairs of substantially horizontal springs, each pair being secured to said bar at one of their ends, and a member disposed between the springs of each pair and secured to their other ends, said members constituting the supports for a bed spring frame.
20. 12. A bed structure having in combination spaced members of a bed frame, a bar spanning and supported by said members, said bar having spaced substantially parallel portions, a pair of springs having one of their ends connected to one of said portions, a pair of springs having one of their ends connected to the other of said portions, a member disposed between said portions and connected at its opposite sides, respectively, to the other ends of both pairs of springs, said member forming the support for a bed spring frame.

In testimony whereof we affix our signatures.

GERHART GANGELHOFF.
MICHAEL JORDAN.
